(57) **CLAIM**

The ornamental design for a device for supporting a flexible bag, as shown and described.

DESCRIPTION

FIG. 1 is a perspective view of a device for supporting a flexible bag showing my new design;
FIG. 2 is a right side elevational view thereof, the left side being a mirror image of that shown;
FIG. 3 is an end elevational view thereof, the other end being a mirror image of that shown;
FIG. 4 is a top plan view thereof; and,
FIG. 5 is a bottom view thereof.
